FIG. 5.

Knut G. Thiman,

INVENTOR,

BY *Frank Carlson*
HIS ATTORNEY.

UNITED STATES PATENT OFFICE.

KNUT G. THIMAN, OF NEW YORK, N. Y.

RULE ATTACHMENT.

1,349,349.

Specification of Letters Patent. Patented Aug. 10, 1920.

Application filed August 14, 1919. Serial No. 317,395.

To all whom it may concern:

Be it known that I, KNUT G. THIMAN, a subject of King Gustavus V of Sweden, and a resident of 165 East 49th street, borough 5 of Manhattan, city of New York, have invented certain new and useful Improvements in Rule Attachments, of which the following is a specification.

This invention relates to carpenters' folding rules and especially to that class wherein 10 slidable attachment enables the rule equipped therewith to be drawn out to take inside measurements.

The chief object of this invention is to 15 provide a simple, inexpensive and perfectly practical attachment for all folding rules, which is easily attached and will enable said rules to accurately measure the inside of boxes between posts, walls or other inside 20 dimensions without shifting the rule.

Referring to the drawing, Figure 1 is a view of a carpenters' rule equipped with an attachment embodying the present invention.

25 Fig. 2 is another view of Fig. 1.

Fig. 3 is a full size view of member 9 of the attachment shown in the previous figures.

Fig. 4 is a full size view of member 5 of the attachment embodying my invention 30 also shown partially in Figs. 1 and 2.

Fig. 5 is an enlarged end view of the members 9 and 5 shown in the previous views when assembled.

The same numerals refer to the same parts 35 throughout the views.

As folding rules are very commonly used by the carpenters, builders and others, I have thought to increase the utility of all such rules by manufacturing a simple attachment which may be easily and permanently attached by anyone that can handle a screw driver.

40 My invention comprises a metal strip 9 whose edges 13 and 14 are turned over in such manner as to enable the strip to retain a second strip 5 whose edges 15 and 16 are bent slightly upward to provide beneath the same clearance for the edges of the first strip. This is particularly illustrated in 45 Fig. 5.

In attaching my invention to a rule, strip 5 is first accurately fitted over the first six inch section 8 of a folding rule and secured 50

by three short screws. Subsequently, strip 9 is slipped on to the outer end and pushed 55 in upon the screwed strip and will be seen to exactly cover the same. This last strip is marked exactly like the section 8 which is covered, and is the substitute therefor in ordinary use.

In order to cause the parts to register properly, stops 3 and 4 have been provided in strip 5 to engage superposed stops 1 and 2 when the outer strip 9 is drawn inward to the limit. When the latter strip is drawn 60 out, its stop 1 will engage stop 4 in the lower strip as the outer limit.

When it is desired to measure the distance between a pair of walls 12 and 11, the actual distance being greater than the length of 70 the six foot folding rule 6, 7 used in this case, it is only necessary to place the last section 10 of the rule to the wall 11, and to draw out strip 9 till it touches wall 12. It is then sufficient to add the reading un- 75 covered on strip 5 and add the same to the length of the rule to have the distance.

It is to be noted, however, that the reading on strip 5 run counter to the normal readings of the rule. This is so for several reasons, among others, so that the first portion of the lower strip shall also be first in notation so that readings will be correct. Also, the readings will be more obvious and less likely to be overlooked.

Naturally, the stops 1, 2, 3, 4 may be differently located according to my own discretion, and I may also employ any metal desirable for manufacturing my invention and I may further use my invention for 90 rules using the metric system. These minor alterations I desire to reserve as my right to use within the scope of my invention.

Having thus fully described my invention, I desire to obtain by U. S. Letters Patent— 95

1. A rule attachment including a strip to be attached to the face of a rule, upturned edges along the sides of said strip providing clearance spaces between said upturning edges and the face of said rule, and 100 means to secure said strip to said rule.

2. A rule attachment including a strip provided with slightly upturned edges along its two parallel sides, a second strip slidably disposed upon said first strip and provided with overturned edges enveloping the 105

upturned edges of said first strip to retain both strips in contact, and means to limit the relative movement of said strips.

3. A rule attachment including a strip to be attached to a rule, and numerically marked in the opposite direction to the part covered, a second strip slidably attached to said first strip having thereon the same numerals and markings as the portion of the rule covered by said first strip, and stops upon said first strip adapted to engage said

second strip in both extreme extended and withdrawn positions.

Signed at 132 Nassau street, in the borough of Manhattan in the county of New York, 15 city and State of New York, this 23rd day of July, 1919.

KNUT G. THIMAN.

Witnesses:

ELIAS JOHNSON,
EDWARD CHILSTROM.
